UNITED STATES PATENT OFFICE

JOHN EDWARD THORNTON, OF WEST HAMPSTEAD, LONDON, ENGLAND

MULTICOLOR CINEMATOGRAPH AND OTHER FILM AND PROCESS OF MAKING SAME

Original application filed May 5, 1924, Serial No. 711,254, and in Great Britain May 18, 1923. Divided and this application filed November 3, 1925. Serial No. 66,604.

Applications for this patent have been filed in Great Britain, No. 13,358 of 1923, 4,009 of 1924, and 18,168 of 1924, all dated May 18, 1923.

5 This invention relates to the manufacture and production of multi-color cinematograph and other film negatives either in four or three colors.

10 The purpose of the present invention is to produce a complete color-group or unit of primary images of the original subject, and similar color-group or unit of secondary images reproduced from the first, in order that such primary or secondary images 15 can be used as printing clichés for producing similar multi-color positives.

This is effected by splitting the light coming from the object photographed into two images of identical size by means of camera 20 and suitable optical devices, and receiving these two images upon a sensitized material of special type, which is of double-picture-area and is provided with two screen-filters each containing a different pair of colors; the 25 result being that two half-picture images are formed on the sensitive material which each represent an analysis of two colors only, the complete group being so constructed that it may comprise either four or three color-analysis 30 resulting from the analysis provided by the two half-picture images.

In a co-pending application Serial No. 711,254, filed May 5, 1924 of which this application is a division, a method is described 35 whereby the two half-pictures or split records formed by this invention are reproduced as two positives of similar type, and these two positives are then superimposed and cemented together, so that they produce a reconstructed single picture (also containing 40 four or three colors as desired) which corresponds in character and in coloring to the original subject photographed.

This specification describes in detail the 45 several steps required to produce the negatives (preferably terms printing-clichés) from which those positives of similar type are produced.

But negatives or printing-clichés of this 50 double-screen type are not necessarily re-

stricted to the production only of positives of the double-screen type, for they can be used for producing positives by several different processes. And they may also be used as the starting point from which a set of four or 55 three full-tone negatives can be reproduced, each representing an analysis of only one color of the group.

Their widest application will no doubt be found in producing, by only one printing-exposure, four-color positive transparencies in the form of thin or thick films, glass plates, lantern-slides, cinematograph films and the like, upon sensitized positive-material which is of similar construction to the negative-material; that is to say which is also of double-area, is provided with two screen-filters each 60 representing a different pair of colors, and is covered with a panchromatic gelatino-silver emulsion. 65

70 By the use of these double area double-screen negatives, and "projection-printing" on to double-area double-screen sensitized positive-material, all the principal difficulties in producing multi-color pictures are 75 overcome; it only being necessary to cut, superimpose and cement the two half-picture positives to produce a complete multi-color picture.

80 The invention can be used with any optical system of lenses capable of producing two adjacent images of one subject, such for example a pair of lenses; but the preferred form of optical system, whereby two images of the same subject are simultaneously formed upon 85 the one film-strip and both photographed from the same viewpoint without showing "parallax" or "fringing" effects, uses only one lens and a light-splitting device, and is fully described in a further application Serial No. 90 66,602 filed November 3, 1925.

In the drawings:—

Fig. 1 shows a portion of a double width strip of transparent support upon which are 95 formed two screen filters each having two colors as shown and formed of interspersed fine lines of different colors.

Fig. 2 is a similar view but with screens only analyzing three colors. 100

Fig. 3 is a similar view to Fig. 1 with screens formed of grains.

Fig. 4 is a similar view to Fig. 2 with screens formed of grains.

Fig. 5 is a similar view to Fig. 1 in which dots form one element of each screen.

Fig. 6 is a similar view to Fig. 2 in which dots form one element of each screen.

Fig. 7 is a section of a double width screen film negative material having a thick celluloid support, substratum layer, a pair of two color filters and a pair of black silver primary images of negative character.

Fig. 8 shows in section, a double width screen film negative material with a pair of secondary images.

Fig. 9 shows a piece of double width film containing a conventional design.

In all the above drawings the lines and dots are shown very coarse and wide apart for clearness of illustration, but in practice are exceedingly fine, the lines being preferably about 500 to the inch and grains finer still. Also the two groups of colors would partially overlap and mix in an actual picture but for clearness they are shown in the diagrams as not overlapping.

For producing non-cinematograph pictures the pair of negatives are formed upon adjacent areas of the sensitive-material arranged in vertical pairs or horizontal pairs.

A double-width negative film-material upon which the pairs of color-screens are arranged side-by-side in two rows is employed.

25 *The invention applied to cinematography*

The following description shows how the invention is applied in the production of multi-color film-negatives on continuous lengths of film for producing cinematograph pictures in series, each picture containing either four or three colors as may be preferred.

The double-width negative-film is intended for printing on to the double-width positive-film by projection methods (either from an original negative after its reversal, or preferably through the intermediary of a printing-cliché (Figure 8) reproduced from the original and reversed in the process of reproduction).

Structure of the negative film-material

The following is a brief and general description of the negative film-material, a more detailed description of which and method of its manufacture is given in application Serial No. 66,603, filed November 3, 1925.

The special film-material upon which the negatives are photographed is of the class known as "screen film". By this is meant that the transparent celluloid base is provided with a color-filter in the form of a very fine multi-colored screen (Figures 1 to 6) printed or formed upon a substratum amalgamated

upon the face of the celluloid (or alternatively it may be printed direct upon the celluloid itself), and this screen is afterwards covered with a panchromatic gelatino-silver-bromide emulsion. But in this invention a special form of "screen-film" is used which is provided with a pair of screens (each different) instead of the usual single type of screen; which are hereinafter more fully described.

The base used for the negative film is preferably of the full standard thickness (about .0045 inch) (Figures 7 and 8), and when the substratum, screens, and sensitized layer are added the total thickness of the negative film is about .0065 inch.

Exposure of this negative film in the camera is made with the transparent base of celluloid or other material facing towards the lens and the sensitized side turned away from the lens, so that light passes first through the transparent base, then through the pair of screens or light-filters, and finally reaches the panchromatic emulsion, upon which it forms a pair of section-images each representing a different pair of color-sensations according to the colors of the light which the filters have allowed to pass.

For four color negatives

The pair of filter-screens for four-color negatives comprise an immense number of exceedingly fine colored dots, lines or mosaic patterns (Figures 1, 3 and 5), a fuller description of which is given in the aforesaid specification Serial No. 66,603. These are arranged in two groups, side-by-side upon the two halves of the double-width film strip (Figures 7 and 8). One screen consists of dots, lines or other pattern of two colors equally intermixed, and the other screen of two other colors equally intermixed. The colors used for a four-color screen-filter set are preferably crimson-red and blue-green for one half of the double-width negative film, and blue-violet and orange-yellow for the other half. These form one filter-set containing the complementary colors of red and green, and another filter-set containing the complimentary colors of blue and yellow. Each half of the double-width film therefore contains its own complementary color, and the two halves are also complementary to each other. This particular arrangement however is not necessarily a hard and fast rule, though it is preferred, for if desired the complementary colors of each pair may be arranged upon the adjoining half-width instead of upon the same half-width.

For three-color negatives

The filter-screens for three-color are of a similar character (Figures 2, 4 and 6), consisting of fine dots, lines, or mosaic pattern, but the colors comprise only crimson-red, blue-green, and blue-violet. They are ar-

ranged in two groups, one upon each half of the double-width film as in the preceding example, but one of the colors is repeated upon each half. For example one half-width may have a filter-screen of crimson-red and blue-green, and the other a filter-screen of blue-violet and blue-green. Or any other preferred arrangement of the combination may be used; for instance by duplicating the yellow filters on the negative-film the complementary color, blue-green, will predominate in the positive film because it will be repeated upon both halves.

Producing the original (camera) negatives

By photographing in the camera upon screen-film of four or three color negative-material of the type already described, images will be produced upon development in the form of a pair of black-silver images of negative character (Figure 7) through which parts of the color-screens can be seen by transmitted light. This means that the colored screen-images visible through the transparent portions of the black-silver negative-images will be of positive character, and not suitable as a printing cliché until the black images have been reversed as hereinafter described.

The camera and optical light-splitting arrangements are so constructed that, when a strip of such double-width color-filter screen-film is exposed therein, the primary image formed by the one lens is split into two secondary images by means of the light splitting device, and thus two separate images are simultaneously formed upon the two halves of one film, as more fully described in the co-pending specification Serial No. 711,254.

If the negative material is of the four-color type each of these images will be again divided by its filter, so that the double-width film will then carry two half-picture negatives side-by-side upon the same film (each recording two colors), making four records of different color-sensations on the one double-width film-strip.

If the negative material is of the special three-color type already described the result will be similar, except that one of the color-sensations will be repeated upon both halves of the double-width.

Producing the printing clichés

Having made the camera exposure and obtained the original negative-records by the method described, it is now necessary to produce a printing-cliché from which the final positive-records (Figure 8) for exhibition can be printed. At this stage therefore either of the following alternative courses are open:-

(A) The original (camera) negative (which is complementary in its coloring to the actual scene photographed) may be used

to produce a corrected positive by printing from the original negative through a lens on to a positive film of similar character, also provided with similar color filters and panchromatic emulsion, in which case the colors 70 on the resulting positive will be again reversed and therefore will be the same as those in the original scene or object.

(B) The original (camera) negative may be treated by the usual reversal baths and treatment by which it can be converted from a negative of incorrect or complementary colors into a positive of correct or non-complementary colors, so that the real coloring of the scene or object is produced on the original 80 film.

(C) A positive in black and white can be reproduced from the colored negative A, or a negative in black and white can be reproduced from the colored positive B, by copying 85 through a lens and camera.

The term printing-cliché is used to cover either the negative or positive form of reproduction matrix.

A printing cliché of the black and white 90 type such as C, reproduced from colored negative A or colored positive B, may be used for direct printing either by contact or by projection upon any of the different types of sensitized material. Such a printing-cliché 95 is best produced from a large projected image by copying, the printing cliché for each of the four colors being photographed separately through color filters which cut out all but the one color to be reproduced.

Or a positive of correct colors such as B may be again used to produce a duplicate negative like the original complementary one.

A certain slight loss or degradation of 105 color occurs with every reproduction, but the amount is not a serious objection in this invention.

Preferred form of printing-clichés

Of these several methods it is preferred in commercial manufacture not to use the original (camera) negative, because of the labour involved in treating continuous lengths of film to the processes of reversal and also because of the danger of damaging the original negative in the processes.

It is therefore preferred to make a reproduction from the original, and further because by making such reproduction the necessary reversal of image is simultaneously effected (Figure 7). Therefore a positive print is made from the original negative by copying in a camera through a lens and developing the image in the usual way, in accordance with method A. This will produce a copy in which the black-silver images will be of positive character, and this copy is used as the printing-cliché from which the 125 actual exhibition positives are reproduced.

Therefore in these final reproductions for exhibition purposes (produced according to the co-pending application Serial No. 66,602 hereinbefore referred to) the black-silver images will be of negative character and the color-screens visible through them will be of positive character.

What I claim as my invention and desire to protect by Letters Patent is:—

- 10 1. A multi-color screen-mosaic picture-negative comprising a transparent support of double picture-area, a two-color mosaic filter-screen upon one area of the support and another two-color mosaic filter-screen upon another area of the support, the two-colors in one screen being different from the two colors in the other screen, the support bearing one component-image behind one screen and another component-image behind the other screen, each component-image being different from the other, one compartment-image and its filter-screen comprising one half-picture and the other component-image and its filter-screen comprising the other half-picture.
- 20 2. The process of producing a multi-color screen-mosaic picture-negative which comprises projecting images of an object on to a sensitized medium through a pair of two-color mosaic filter-screens arranged side by side, the colors in one screen being different from the colors in another screen, whereby component-images are formed on the sensitized medium behind the respective screens.
- 30 35 In testimony whereof I have hereunto set my hand.

JOHN EDWARD THORNTON.
